UNITED STATES PATENT OFFICE.

CHARLES F. REICHARDT, OF WOODHAVEN, NEW YORK.

WINDOW.

1,174,445.

Specification of Letters Patent. Patented Mar. 7, 1916.

Application filed November 14, 1913. Serial No. 800,918.

To all whom it may concern:

Be it known that I, CHARLES F. REICHARDT, of Woodhaven, in the county of Queens and in the State of New York, have invented a certain new and useful Improvement in Windows, and do hereby declare that the following is a full, clear, and exact description thereof.

My invention relates to windows in general that are adapted to close automatically, but it relates particularly to windows which will close automatically in case of fire.

The object of my invention is to provide a self-closing window which will become effectively closed in case of fire and which is so constructed that the operating parts will not cause the window to bind in any way during the automatic closing and during the operation of the window after the automatic closing thereof. The last mentioned object of my invention is particularly important when it is desired to enter a building after the window has become closed automatically, inasmuch as at that time it becomes necessary frequently to raise or open the window in order to gain access to the building.

One object of my invention relates particularly to providing a window of this character which may be readily opened after it has become automatically closed.

A further object of my invention is to provide an improved form of fusible link in window-supporting mechanisms, which link is so constructed that it will readily pass over the pulleys provided for window chains and which, while being exceedingly strong in construction will readily become disengaged under the influence of heat to cause the window to close automatically.

While my invention is capable of embodiment in many different forms, I have shown only one form thereof in the accompanying drawings, in which—

45 Figure 1 is a front elevation of a window equipped with my own invention; Fig. 2 is a perspective view of the same, showing the window in open position; Fig. 3 is a similar view, showing the window in closed position 50 after the window has been automatically closed, and Fig. 4 is a perspective view of a portion of the chain, showing one of the fusible links. Fig. 5 is a perspective view of a weight having a detachable bracket; Fig. 6 is a different perspective view of the same; and Fig. 7 is a perspec- 55

tive view of the complementary weight attached to the lower sash.

In the drawings I have shown a window frame 1, carrying a lower sash 2 and an upper sash 3. The frame and sashes are preferably made of sheet metal. The lower sash 2 is supported at each side thereof by a pair of weights 4 and 5, the weights 5 having dove-tailed grooves 6 to receive dove-tailed extensions 7, carried by the weights 4. Each of the weights 4 is provided with a horizontally directed detachable bracket 8, having an opening 9 to receive the chain which supports the weight attached to the upper sash 3. The weights 5 and 4 are preferably so proportioned that the weights 4 weigh less than the weights 5 and if desired, the weights 4 may weigh only one-half as much as the weights 5. As shown in the drawings, each of the weights 5 is attached by means of a chain 10 of any usual construction to the top of the lower sash 2, said chain passing over a pulley 11 secured to the top of the window frame in the usual manner. The weights 4, on the other hand, are connected to the lower sash 2 by means of a chain 12, which passes over pulleys 13 attached to the top of the window frame in the usual manner and downwardly through the frame of the lower sash 2 and beneath the same in such a manner that the chain 12 extends entirely around the three sides of the lower sash 2 with a portion of the chain extending across the end surface of the lower sash 2 in an exposed position. The chain 12, above the top of the lower sash 2 and at the bottom of said sash, is provided at intervals with fusible links 13^a. These links are constructed from two eyelets 14, each of said eyelets having a pair of leaves 15, which fit together telescopically and are secured together by means of solder or some other fusible composition which will cause the two parts of the fusible link to become separated under the influence of heat. These fusible links are, furthermore, of such a construction that they will readily pass over the pulleys 13. The upper sash 3 is supported by a pair of weights 16, which are attached to the sash 3 by means of chains 17 extending over supporting pulleys 18, secured to the top of the window frame in the same manner as the pulleys 11 and 13, already described.

In the normal operation of windows sup-

ported in the manner described, the window sashes 2 and 3 will be properly balanced by the weights 4 and 5 and the weights 16, respectively, so that the window sashes 2 and 5 3 may be raised and lowered at will in the usual manner. During the raising and lowering of the window sash 2 the weights 4 and 5 will remain in engagement with each other and there will consequently not be any 10 opportunity for these weights to become entangled with each other nor, in fact, with the weights 16, which support the other sash 3. Assuming that the window is open, in 15 case of fire one of the fusible links 13^a in chain 12, either at the side of the window frame above the top of the lower sash 2, or below the bottom thereof, will be acted upon by the heat so as to cause the fusible composition holding the parts of the fusible link 20 together to become melted, thereby disconnecting the parts of the fusible link and severing the chain 12 in which it is situated. When any one of the fusible links becomes disconnected in this manner, both of the 25 weights 4, to which the chain 12 is attached, will immediately fall, thereby disengaging themselves from the weights 5 and falling upon the tops of the weights 16. The decrease of the size of the supporting weights 30 for the lower sash 2 will immediately cause the lower sash to fall to the bottom of the window frame, thereby closing the same. Furthermore, the falling of the weights 4 upon the weights 16 will so increase the 35 weights attached to the upper sash 3 as to cause the same to become immediately closed. This operation of closing the window is not only such as to cause the same to be closed when any one of the links 13^a 40 becomes disconnected in the manner indicated, either at one side of the window or at the bottom thereof, but the release of the weights will be such as to cause the re-adjusted weights attached to the two sashes 2 and 3 45 to exercise even pressures upon the two sides of the particular window sash. By this means any danger of the window sashes becoming jammed or binding so as to prevent the proper operation of the same is entirely 50 avoided. It is not only necessary to avoid the binding of the window during the auto-

matic closing of the sashes therein, but it is also necessary to avoid binding of the same when subsequently it is desired to open one of the sashes in order to enter the building 55 through the window, which frequently happens immediately following the discovery of a fire therein. Furthermore, the arrangement of the weights in such a manner that the majority of the supporting body of 60 metal for the lower sash 2 is still attached to said sash, even after the automatic closing of the same enables the lower sash to be readily raised when it is desired to open the window to enter the building after the discovery of a fire. This is a distinct advantage, inasmuch as it is very desirable to be able to raise the lower sash readily and quickly after a fire has been discovered and when it is desired to enter the building. 65 Again, the use of detachable brackets 8 permits a bracket of the proper length for a particular window to be readily applied.

While I have described my invention above in detail, it is to be understood that 75 many changes may be made therein without departing from the spirit of the invention.

I claim:

1. In combination a window sash and means for supporting the same comprising 80 a weight and a chain connecting the weight permanently to the sash, an auxiliary weight attached to the sash and a chain connecting the auxiliary weight to the sash and having fusible links said weights being dovetailed 85 together for relative longitudinal, but not lateral movement.

2. In combination a window sash and means for supporting the same comprising 90 a weight and chain connecting the weight permanently to the sash, an auxiliary weight attached to the sash and having fusible links, said weights having interlocking projections and recesses interlocking the weights together for relative longitudinal but not 95 lateral movement.

In testimony that I claim the foregoing I have hereunto set my hand.

CHARLES F. REICHARDT.
